UNITED STATES PATENT OFFICE.

HERBERT C. BLISS, OF ATTLEBORO, MASSACHUSETTS.

DESIGN FOR A BRACELET.

42,412.

Specification for Design.

Patented Apr. 23, 1912.

Application filed March 10, 1911. Serial No. 613,669. Term of patent 7 years.

To all whom it may concern:

Be it known that I, HERBERT C. BLISS, a citizen of the United States of America, residing at Attleboro, in the county of Bristol and State of Massachusetts, have invented a new, original, and ornamental Design for Bracelets, of which the following is a specification, reference being had to the accompanying drawing, forming a part thereof, in which—

Figure 1 is an edge elevation, and Fig. 2 is an enlarged face view of a bracelet, showing my new design.

As shown in the drawings, the leading and material feature of my design consists in the configuration of the exterior face of the bracelet, the central portion A being in the form of a relatively wide band slightly curved or convexed with its marginal edges B having an abrupt downward inclination

meeting with the adjacent marginal edges of the intermediate beads C which latter terminate in the marginal beads D. The marginal beads have curved or convexed exterior faces more abrupt than the exterior face of the central band A and are of materially greater width than the intermediate beads C which latter are in the form of steps, the beads D joining with the beads C and forming annular V-grooves E.

I claim:

The ornamental design for a bracelet as shown and described.

In testimony whereof I have affixed my signature in presence of two witnesses.

HERBERT C. BLISS.

Witnesses:

ERNEST M. BLISS,
WILLIS H. STREETER.
